UNITED STATES PATENT OFFICE.

HAVARD F. HUDSON, OF WICHITA, KANSAS.

FLUSH VALVE.

Application filed July 28, 1923. Serial No. 654,346.

To all whom it may concern:

Be it known that I, HAVARD F. HUDSON, citizen of the United States, residing at Wichita, county of Sedgwick, and State of Kansas, have invented certain new and useful Improvements in Flush Valves; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to improvements in flush valves of the type employed in connection with toilet fixtures and sometimes referred to as "flushometers."

It is well known that the ordinary flushing apparatus employed in connection with toilet fixtures are unsightly and are often unsatisfactory in their operation. In order to enable the tank and allied float-operated valve to be dispensed with, it has been proposed that the same shall be replaced by a valve mechanism that will permit a predetermined amount of water to flow, which can be controlled by a pilot valve and which will automatically close.

It is the object of this invention to produce a flushometer that shall be of simple and substantial construction, of neat and pleasing appearance, and which shall be so constructed and designed that it will be positive and reliable in its operation.

The above and other objects which will appear as the description proceeds, are attained by means of a construction which I will now describe in detail, reference for this purpose being had to the accompanying drawing in which the preferred embodiment of my invention is shown, and in which:

Fig. 1 shows a side elevation of a toilet fixture which is equipped with my improved flush valve.

Fig. 2 is a vertical section through the valve and shows the relationship of the parts.

Fig. 3 is a transverse section taken on line 3—3, Fig. 2.

Fig. 4 is a detail showing a modified form of construction.

Fig. 5 is a section taken on line 5—5, Fig. 4,

Fig. 6 is a side elevation showing the appearance of my modified form of construction. 55

Fig. 7 is a longitudinal sectional detail showing a booster that is occasionally required to be embodied in the combination. 60

Fig. 8 is a vertical section through a house showing the relationship of the various elements of my combination.

Fig. 9 is a side elevation of my improved pressure booster tank with portions thereof 65 broken away.

Fig. 10 is a section taken on line 10—10, Fig. 9.

Fig. 11 is a modified form of pressure tank wherein the air is contained in an air-tight bag, and this view is shown partly in section. 70

Fig. 12 shows a diametrical section of a modified form of pressure tank; and

Fig. 13 is a section similar to that shown 75 in Fig. 12 but differs therefrom by having a flexible metal diaphragm.

The same reference characters will be employed to designate the same parts throughout the several views. 80

Numeral 1 represents the floor and 2 the wall of a toilet or bathroom. A bowl 3 rests upon the floor 1 and is connected to the plumbing in the usual manner. A pipe 4, which is preferably one inch or larger, 85 connects directly to the water supply. The flow of water through the pipe 4 is controlled by means of my improved valve which I will now proceed to describe:

My valve consists of a body member 5, 90 made somewhat in the shape of a T. The laterally projecting portion 6 is internally threaded and is designed to connect to the bowl in the manner shown in Fig. 1. The upper end 7 is externally threaded and adapted to receive a cap 8 of a union by means of which the body member 5 is connected to the lower end of pipe 4. The lower end 9 of the member 5 is externally threaded and has attached thereto a cylinder 10 within which is reciprocably mounted a piston 11. A piston rod 12 is connected to the piston and has secured to the end thereof a rubber or metal ball 13 which engages the inclined sides 14 of the opening 15. 100 When the piston 11 and the valve member 13 are in their lower position, as shown in Fig. 2, the ball valve 13 will close the exit 105

from pipe 4 so that no water can flow out therefrom, similar to an ordinary check valve. If sufficient pressure is applied to the bottom of the piston 11 to force the valve member 13 from its seat, water will flow into the interior of member 5, through the projecting portion 6, through the pipe 4, and into the bowl 3. Secured to the lower end of the cylinder 10 is a cap 16 provided with a central tubular member 17 which terminates in a threaded portion 18. A pipe 19 extends from the threaded end 18 to the valve 20, wherever it may be located for the convenience of the user, and is secured to the end 18 by means of a cap 21. The valve casing 20 has a central opening 22 with which the pipe 19 connects. The opening 22 connects with the enlarged portion 23, the inclined conical walls 24 forming a valve seat for cooperating with the valve 25, which is secured to the inner end of the valve stem 26. The stem 26 extends out through the gland 27 and terminates in a head 28. A spring 29 surrounds the stem and abuts its ends against the head 28 and the cap 30 and tends to hold the valve member 25 against the valve seat 24. A pipe 31 extends from the supply pipe 4 to the pilot valve 20 and has its upper end connected to pipe 4 by means of suitable couplings such as shown in Fig. 2 or by other suitable means, and a fine screen 19^A, as drawn, is inserted therein to keep dirt out of the top of the valve. If pressure is exerted on the handle 28, sufficient to move the valve member 25 from the seat 24, it is apparent that water will flow through pipes 31 and 19 into the bottom of the cylinder between the cap 16 and the piston 11. Since the area of the piston is greater than the cross-sectional area of the valve member 13, it is evident that a greater force will be produced tending to move the valve to open position than is exerted in the opposite direction, and the valve will therefore open and permit water from the pipe 4 to flow into the interior of member 5. When the valve 25 is closed, the water within the cylinder will become trapped, so to speak, and would maintain the valve 13 in open position indefinitely, which, of course, would not be desirable. I have therefore provided the cylinder with a channel 32 which extends practically the entire length thereof between the threaded portion at each end. The trapped water which was employed for the purpose of opening the valve can escape through the channel 32, thus allowing the valve to close. By properly proportioning the size or cross-sectional area of the groove 32, the valve 13 can be made to remain open a sufficient length of the time to effect the necessary flushing of the bowl. The amount of water required to properly flush a bowl depends on several varying factors and the length of

time the water must flow is also different for different installations, depending, among other things, on the pressure of the water supply and the style and water-carrying capacity of the bowl. I have therefore found that I must provide means whereby the rate at which the valve closes can be adjusted to suit the conditions under which the valve operates. I make the cross-section of the groove 32 sufficiently large to permit the valve to close in the minimum time required. Where it is desirable to make the valve close more slowly, I employ an adjusting means comprising a screw 33 whose end projects into the groove 32. A projecting threaded lug 34 is provided on the cylinder and threadedly connected to this is a cap 35 which forms with the end of the lug a chamber for the reception of packing material 36. When the effective cross-section of the groove is to be decreased in order to slow down the motion of the piston, the screw 33 is turned so that the end thereof projects into the groove thus reducing the area of the opening through which the water must flow.

The movement of the cylinder surface past the screw 33 tends to facilitate the removal of any dirt that collects at this point and keeps the passage open and in operative condition. The force which tends to close the valve 13 is the resultant of three different forces produced as follows:

First, the pressure of the water in pipe 4 and its friction against the valve member 13 produces a force which tends to close the valve; second, the reaction of the water from the valve 13 against the upper surface of the piston, this last force being considerable, as the water must change its direction 90 degrees or more; and, third, the weight of the piston pulls valve 13 into a closed position on the principle of a check-valve. The operation of the valve mechanism described above is as follows:

The pipe 4 is connected to the supply which must be ample to cause a good flow of water through this pipe. This pipe must be one inch or larger. With valves 13 and 20 in closed position, no water will flow from pipe 4 and valve 13 will remain firmly seated against the valve seat due to the force produced by the water which is equal to the pressure times the area of the valve member at the point where it contacts with the seat. I will call attention at this point to the fact that the valve seat 14 and the valve member 13 contact along surfaces which are inclined to the axis of the valve. The pressure perpendicular to the contacting surfaces is therefore greater than the force in the direction of the axis and varies inversely as the sine of the angle which the surfaces in contact make with the axis, thus creating a positive closing contact pressure

which eliminates leakage without the necessity of increasing the area of valve 13 to obtain this required contact pressure.

Let us suppose that the parts occupy the position shown in Fig. 2 and that pressure is exerted on the head 28 sufficient to open the same. Water will then flow through the pipe 31, through valve 25, through pipe 19 and into the space between the cap 16 and the head of the piston 11 and move the latter upwardly, thereby opening the valve 13. After valve 13 has been fully opened, the valve 25 is closed. The water in the cylinder below the lower surface of the piston 15 will now have no other way of escape than through the groove 32 and the valve 13 will close, but only as fast as the escape of water through the channel 32 permits and this can be regulated by means of the screw 33. As the valve closes gradually and in accordance with the rate at which the water can escape through the channel 32, there will be no tendency for the piston and valve 20 to "hammer" and the valve will operate 25 quickly and silently.

It is apparent that the valve need not be directly attached to the toilet bowl or located in the position shown in Fig. 1, but that it can be located at any reasonable distance therefrom and the discharge port 6 connected to the fixture by means of a pipe 4. The valve can therefore be located at any convenient place in the wall, floor or in the basement of the house and pipes 19 and 31 30 extended to the pilot valve 20 which must be located within convenient reach of the toilet fixture.

In Figs. 1 and 7 I have shown an element indicated by the numeral 37, which I term 40 a "pressure booster". This pressure booster is merely an enlarged portion of pipe 4 and may be formed integrally therewith as shown in Fig. 7, or separately and connected to two adjacent ends of the pipe. The 45 water enters the pressure booster in the direction of the arrow 38 and the lower end of the upper section of pipe 4 projects into the pressure booster chamber in the manner indicated at 39 in Fig. 7. The pipe 31 is 50 connected to the side of the pressure booster chamber in the manner shown in Fig. 7. The purpose of the pressure booster is to increase the pressure of the water at the point where the pipe 31 is connected, so that the 55 pressure on the head of the piston will be greater than it otherwise would be when the water in pipe 4 is flowing.

The pressure booster operates on the same principle as a Venturi meter, namely, that 60 when the velocity of flow is increased at a given point, the pressure at the point of increased velocity will decrease and conversely, when the velocity is decreased, as it will be when the cross-sectional area of the pipe 65 is increased, the pressure at this point is in-

creased. The projecting flanges 39 serve to increase the effect which would otherwise be produced, due to the production of what is called an "entrance back pressure" which is present wherever water flows from a larger 70 pipe into a smaller pipe. The increased pressure, due to the decrease in the velocity and to the entrance head, is added to the pressure normally present in the supply pipe 4 when the water is flowing therein, and this increased pressure acts on the piston for 75 opening the valve 13 when the valve 25 is opened. As a rule the pressure booster is not necessary because the diameter of the piston can be made so large that it will open 80 and maintain the valve in open position under all circumstances. If, for any reason, it should be necessary to increase the pressure on the piston above that ordinarily obtainable, this can readily be accomplished by 85 the addition of the pressure booster in the manner described. This valve 13 will operate equally well in the reversed position, except where the pressure is extremely low, in which latter case the weight of the piston 90 greatly aids in closing the valve.

I have already called attention to the noiseless operation of my valve, which is due to the fact that it can close only as fast as the water escapes through the groove 32. 95 As water is incompressible, the piston can move only at a very slow rate which may be decreased toward the end of the stroke by the simple expedient of decreasing the cross-sectional area of the channel 32 near 100 the top of the cylinder.

In order to adjust for wear, which will gradually cause water to leak by between the sides of the piston and the cylinder surface, it is only necessary to turn the screw 105 33 in a direction to further decrease the cross-sectional area of the opening through which the water has to flow to the extent necessary to compensate for the added leakage, due to wear.

It is evident that if the valve should remain open the same length of time, regardless of the pressure of the water in the supply pipe 4, too much water would be used 115 when the pressure of the supply was high and too little when the pressure was low. The construction of my valve compensates for this difference in pressure so that the valve will close faster when the pressure of the supply is high than when the pressure is low. The reason for this is that the force 120 acting on the piston, tending to move it toward closing position, varies directly with the pressure of the water in the supply pipe and the rate at which the water will flow outwardly through the channel 32 is directly proportioned to the pressure exerted on the piston. Therefore the faster the water flows through the valve 13, the faster the valve 125 will close.

The arrangement of the piston 11, the bypass or channel 32 and the adjusting screw 33, shown in Fig. 2 and described above, is considered satisfactory and takes care of all dirt found under normal conditions, due to the self-cleaning, wiping action of the piston past the point of screw 33, but in order to obviate, to the greatest possible extent, the danger of stoppage, due to dirt clogging the channel 32, I have designed an alternative construction shown in Figs. 4, 5 and 6. In this construction the cap 16, shown in Fig. 2, is replaced by a cap 161 having a central tubular member 40 whose lower end 41 is closed and provided with a lateral nipple 42 to which the by-pass pipe 43 is connected. This pipe has its other end connected to the cylinder 10 at a point above the highest point reached by the piston 111. Secured to the head of the piston is a rod 44 which fits the opening in the tubular member 40, which opening is preferably cylindrical and has one side flattened in the manner shown in Figs. 4 and 5. A screw 333 has a threaded connection with the inside of the tubular nipple 45 and has its inner end flattened so that it will cooperate with the flattened surface of the rod 44. By rotating the screw 333, the opening between it and the flattened side of the rod 44 can be adjusted at will. As the rod 44 cannot rotate, due to the action of the screw and the flattened side, and as the piston 111 is free to rotate, it is evident that the rod 44 must be attached to the piston by means which permit relative rotation. I have therefore provided the upper end of the rod 44 with an enlarged head 46 which fits into a cavity in the head of the piston and is held in place by a suitable plate 47. The valve casing 20 is connected to the cap 161 and controls the water under pressure that opens the valve by raising piston 111. When water is admitted to the cylinder below the lower surface of the piston, the latter naturally moves upward as long as the valve 25 is held in open position until it has reached the limit of its upward travel. When valve 25 is closed the water in the lower end of the cylinder has no way of escape, except through the tubular member 40 and the pipe 43 and therefore the piston 111 can move downward only as fast as the water escapes through 40, 42 and 43 to the upper end of the cylinder and the rate of escape through this passage can be controlled by means of the screw 333 in the manner explained. Since the rod 44 reciprocates as the piston reciprocated in the cylinder, it will always keep the opening clean.

When the pressure is sufficient and the house has a sufficiently large supply pipe, which should be at least a one inch pipe, the valve can be installed in the manner

shown and described above, but where the supply pipe to the building is small and where the pressure is lower than it should be, I install a pressure flow increasing tank in the supply line in the manner shown in Fig. 8. The flow booster tank comprises a cylindrical steel container about 24 inches high and 12 inches in diameter, although smaller or larger tanks may be employed. The water supply from the mains and the outlet to the toilet fixtures are both connected near the bottom of the tank so that when water is admitted thereinto the air contained in the tank will be compressed in the upper end of the tank, all in a manner that is broadly old and which will be hereinafter described more in detail.

It has been found that where pressure flow booster tanks of the general type referred to have been installed, difficulty has invariably been experienced, due to the fact that the air in the tank will be gradually absorbed by the water and that after some time the air supply therein will fall below that which is necessary for successful operation. When the air supply becomes too low, it is necessary to disconnect the piping or take other means for replenishing the air supply.

In order to overcome the difficulty referred to above, I have constructed my tank in such a manner that any absorbed air will be separated from the water as the latter leaves the tank. There are two well known ways of separating absorbed air from water. One is to heat the water and the other is to decrease the pressure. It is, of course, not practical to heat the water that is used for flushing a toilet and therefore this method may be disregarded. Where a pressure flow increasing tank is employed, the pressure is decreased whenever the toilet is flushed and therefore a large amount of the absorbed air is automatically released at the time that the flushometer is operative. Although the periodic reduction of the pressure liberates a large amount of the absorbed air when the water from the main is normally well charged with air, yet when the water from the main is deficient in air content, then enough air is retained by the water to gradually deplete the supply in the tank. I have found that if I impart to the water in the tank a rotary motion at its time of leaving, when the decrease of pressure liberates a part of the absorbed air, then the centrifugal forces will throw these minute bubbles of liberated air to the center and out of the water and into the top of the tank where the air is needed. I have therefore arranged the supply pipe from the mains in such a manner that the water will enter the tank in a tangential direction. This will cause the water to rotate and the centrifugal action will operate to move the air towards

the center of rotation where the minute air bubbles will coalesce and form larger bubbles which will rise to the surface and join with the air in the tank. By this simple expedient, I have obtained results that are a great improvement over the ordinary arrangement.

In Fig. 8 I have shown a vertical section of a house showing the manner in which my booster pressure tank 50 is connected in the supply pipes to the fixture 3. The pipe 51 connects the tank 50 with the water supply and may be of any size. This pipe has its end secured to the side of the tank in the manner shown most clearly in Fig. 10 so that the water when it enters will be given a rotary motion in the direction of the arrows 52. If we assume a condition to exist in which the flushometer is closed and the piping, including the flow booster pressure tank 50, are empty and then turn the water into the same through the supply pipe 51, the water will flow into the tank 50 and as it cannot leave through the pipe 4, it will compress the air above the surface of the water until the air pressure becomes equal to the water pressure when further flow of water will cease. The pipe 4 should be at least a one inch pipe and therefore where the flushometer valve is opened, the water in the tank 50, impelled by the force of the compressed air, will rush through the pipe 4 at a rate corresponding to the pressure of the air, regardless of the capacity of the supply pipe 51. As the water leaves through the pipe 4, the pressure on the inside of the tank will decrease and this permits water to enter through pipe 51 with the result that the water in the tank will be caused to rotate, as above explained, and this concentrates the air and causes it to become separated from the water.

Although the rotary motion imparted to the water assists greatly in the liberation of absorbed air and will maintain the air supply when the water from the main is adequately charged with air, yet in cities where the water is inadequate in air content, some of the air will invariably be carried away from the inside of the tank, with the result that the remainder will, after awhile, become too small in amount to properly operate the flushometer. In order to automatically increase the volume of gas in the tank, I have provided the following means:

I provide a carbide generator consisting of a cup-shaped member 53 which is adapted to contain a quantity of carbide 54. The cup 53 is provided about its top with an outwardly extending flange 55 which is adapted to be secured to a corresponding flange of the cap member 56 by means of bolts 57. A pipe 58 is connected to the tank 50 at a point sufficiently near the top to be above the liquid level when the nor-

mal quantity of air or gas is compressed to the pressure of the water supply. Pipe 58 connects with and projects into the acetylene generator and is preferably provided with a valve 59 by means of which the effective opening therethrough may be regulated. A second pipe 60 connects the top of the acetylene generator with the top of the tank 50. This pipe has a valve 61 which, together with valve 59, serve to close the pipes whenever the carbide supply is to be renewed. It is evident that whenever the water level extends above the level of pipe 58 that water will enter this pipe and flow through the same and come in contact with the carbide. Acetylene gas will then be generated and this will flow into the tank until the volume of the gas will force the water down below the level of pipe 58. The valve 59 should be so adjusted that the water will only enter the generator drop by drop or at least very slowly so that the generation of gas will not become excessive. Gas will be generated for some time after the water has been forced down below the level of the pipe 58 and this will cause the level of the water to be moved downwardly to such an extent that it will take some time for the water to absorb a sufficient amount of air or gas to again enable it to enter the pipe 58.

By the arrangement just described, it is evident that the gaseous medium in the tank 50 will always be automatically replenished whenever the occasion requires.

The above described automatic gas replenishing means is not absolutely necessary where the water is given a rotary motion in the manner described, as this alone will prevent the air from being depleted for a very long time, when the supply water is deficient in air content, but can be applied in addition whenever the conditions require that the tank shall remain fully operative for very long periods. I have also shown a valve 62 and a stem 63 to which an air pump may be attached for the purpose of increasing the amount of air in the tank. It is evident that the gas generator may be omitted and air introduced by means of a pump when automatic operation is not imperative.

In Fig. 11 I have shown a tank 64 which may be used instead of tank 50. This tank may be smaller than tank 50 and the air, instead of being in contact with the inside of the tank and with the water, is contained in an air-tight bag 65 which may be made of rubber like the inner tube of an automobile tire, or it may be made of rubberized canvas.

The bag 65 is of such size that it fills the tank 64 and is separated from the sides about the opening 66 by means of a fo-raminated plate 67. Air is admitted into

the bag by means of a valve stem 68, such as is employed in connection with inner tubes. Since the air within the bag can be under considerable initial pressure, it is evident that the tank can be much smaller than tank 50 for the reason that it is only necessary that the air be compressed in volume to the extent of the volumetric quantity of water required to flush the toilet fixture. As the pressure of the air on the inside of the bag is the same as the pressure of the water on the outside, it is evident that there is no tendency for the air to flow out, except during the short interval of time during which the tank is emptying. Since the bag 65 is kept cool by the water and is protected from the light and the drying action of the air, it will last almost indefinitely.

20 Instead of a tank like that shown in Fig. 11, I may utilize one made like that shown in cross-section in Fig. 12. In this modification the tank is made of two substantially identical members 69 and 70, each provided with flanges 71 between which a rubber diaphragm or a loose fitting rubberized canvas bag 72 is clamped by means of bolts 73. A valve stem 74 permits air to be pumped into the space between the member 69 and the diaphragm 72 until the latter assumes the dotted line position. The pressure of the air and the size of the parts should be such that when the air pressure has reached that of the water supply, then the diaphragm shall have been displaced to such an extent that the water between it and the side of member 70 is sufficient to flush the toilet.

40 In Fig. 13 I have shown an arrangement which differs from that of Fig. 12 merely in this, that the rubber diaphragm 72 is replaced by a corrugated metal diaphragm 75 made in the manner common in aneroid barometers. When either one of the modifications shown in Figs. 11, 12 and 13 are used, the air does not come into contact with the water and consequently there can be no loss by absorption.

When it is desired that the piston shall move to normal or closed valve position at a variable rate of speed, the surface of the rod 44, which cooperates with the end of the screw to delimit the area of the opening through which the water passes, can be curved so as to enlarge or diminish the space at different points of the stroke.

Although attention has previously been called to the fact that there are three separate forces acting to close the valve when it has been opened, I wish to emphasize this feature of the construction, as it is exceedingly important. The valve 13 is located on the supply side of the seat and consequently is acted upon by the pressure of the water; then the friction of the water as

it flows by the valve and its momentum acting upon the top of the piston, while last but not least, the weight of the piston tends to close the valve. The valve acts similar to that of an ordinary check-valve and requires no pressure on the piston to hold the valve closed. This avoids pressure on the piston and prevents leaks. By putting the valve 13 on the pressure side, I do not have any need of pressure on the piston and this prevents any tendency to leaks. I consider that the arrangement of valve and cylinder in which the valve is on the pressure side of the valve seat and in which the three forces, pointed out above, tend to close the valve is new in my construction and forms a part of my invention.

From the above description, it is evident that I have produced an improved flushometer that is of simple and substantial construction and which can be readily attached to existing toilet fixtures without alteration thereof. I have also produced a combination of means whereby the flushometer can be employed even where the capacity of the supply is insufficient to supply the necessary amount of water. I have also produced a pressure booster tank provided with means whereby air will not be absorbed by the water and carried away, and which cooperates with the broad combination to the extent that it prevents the same from becoming inoperative, due to the depletion of air in the tank.

Having now described my invention, what I claim as new is:

1. A flushometer comprising a body member formed in the shape of a T, said member having two axially aligned openings, and a third opening communicating with the first-mentioned openings, a conical valve seat in one of said aligned openings, a valve member cooperatively related to the valve seat, the opening having the valve seat being adapted to have the water supply pipe connected thereto, a cylinder connected to the body member, a piston in said cylinder, means for operatively connecting the piston and the valve member, a cylinder head secured to said cylinder, a pipe connecting the space between the end of the piston with the supply side of the valve, a normally closed valve in said pipe, said cylinder wall having a groove on its inner surface and a screw operatively associated with said groove for the purpose of adjusting the effective area thereof.

2. A flushometer comprising, in combination, a valve, means for opening and closing said valve, said means comprising a cylinder, a piston slidably mounted therein, means comprising a rod for connecting the piston to the valve, said chamber having a groove on its inner surface for forming a passage connecting spaces at opposite ends

of the piston, and means for controlling the effective area of said passage, said means comprising a screw operatively related to said groove and adapted to control the effective cross-sectional area of said passage.

3. A flushometer comprising, in combination, a valve, means for opening and closing said valve, said means comprising a cylinder, a piston slidably mounted therein, means comprising a rod for connecting the piston to the valve, said chamber having a groove on its inner surface for forming a

passage connecting spaces at opposite ends of the piston, and means for controlling the effective area of said passage, said means comprising a screw operatively related to said groove and adapted to control the effective cross-sectional area of said passage, and a portion of the outer surface of the piston being movable past the end of the screw, whereby a cleaning action is obtained.

In testimony whereof I affix my signature.
HAVARD F. HUDSON.
